Primary Examiner — Jonathan J Han*Assistant Examiner* — Caitlin Mackenzie Williams(74) Attorney, Agent, or Firm — Banner & Witcoff, Ltd.(57) CLAIM

The ornamental design for a shoe as shown and described.

DESCRIPTION

FIG. 1 is a front perspective view of a shoe showing my new design;
FIG. 2 is a side view thereof; and,

FIG. 3 is a rear perspective view thereof.
The broken lines immediately adjacent to the bottom of the shaded area define the bounds of the claimed design and form no part thereof. The broken line showing of the three circular shaped elements represent eyelets that form no part of the claimed design. The broken line showing of the eighteen elongated thin regions represent grooves that form no part of the claimed design. The broken lines depicting the remainder of the shoe form no part of the claimed design.
